CLAIM

The ornamental design for a prefab house, as shown and described.

DESCRIPTION

FIG. 1 is a top-left perspective view of a prefab house showing the new design;

FIG. 2 is a bottom-right perspective view thereof;

FIG. 3 is a left-side elevational view thereof;

FIG. 4 is a right-side elevational view thereof;

FIG. 5 is a front elevation view thereof;

FIG. 6 is a back elevation view thereof;

FIG. 7 is a top plan view thereof;

FIG. 8 is a bottom plan view thereof; and,

FIG. 9 is an enlarged, partial perspective view of the prefab house showing the portion within area 9 of FIG. 1.

The broken lines depict portions of the article that form no part of the claimed design.

The dot-dash lines depict the boundaries of the enlarged view and also form no part of the claimed design.

1 Claim, 9 Drawing Sheets
